UNITED STATES PATENT OFFICE

JULIUS E. JODRY, OF SCRANTON, PENNSYLVANIA.

DESIGN FOR A BICYCLE REPAIR-TOOL.

SPECIFICATION forming part of Design No. 29,718, dated November 22, 1898.

Application filed October 27, 1898. Serial No. 694,747. Term of patent 14 years.

To all whom it may concern:

Be it known that I, JULIUS E. JODRY, a citizen of the United States, residing at Scranton, Pennsylvania, have invented and produced a new and original Design for a Bicycle-Tire Repair-Tool, of which the following is a specification.

In the accompanying drawings, Figure 1 is a side elevation of the design, and Fig. 2 is a plan view of the same.

As shown in the figures, the leading feature of my design is in the shape of the tool. It consists of a shank A, having the lower end bent at an angle, and this lower end has

curved sides terminating in a point, and, as 15 shown, the upper and lower sides of the end are roughened.

Having thus described my invention, what I claim is—

The design for a bicycle repair-tool as herein 20 shown and described.

In testimony whereof I affix my signature in presence of two witnesses.

JULIUS E. JODRY.

Witnesses:

M. L. LANGAN,
D. L. FICKES.
